(57) **CLAIM**

The ornamental design for a world marker mat, as shown and described.

DESCRIPTION

FIG. 1 is a top plan view of a first embodiment of a world marker mat of this invention;

FIG. 2 is a top plan view of a second embodiment of a world marker mat of this invention; and,

FIG. 3 is a top plan view of a third embodiment of a world marker mat of this invention.

In the drawings, the broken lines depict portions of the world marker mat that form no part of the claimed design. Views not shown form no part of the claimed design. The stippling is employed only to represent contrasting color.
